UNITED STATES PATENT OFFICE.

GEORGE W. SCHELLER, OF BROOKLYN, NEW YORK.

BOTTLE-CLOSURE DEVICE

1,051,920.

Specification of Letters Patent.

Patented Feb. 4, 1913.

Application filed April 24, 1912. Serial No. 692,790.

To all whom it may concern:

Be it known that I, GEORGE W. SCHELLER, a citizen of the United States, and residing at 187 Park avenue, Brooklyn, in the county 5 of Kings and State of New York, have invented certain new and useful Improvements in Bottle-Closure Devices, of which the following is a specification, such as will enable those skilled in the art to which it 10 appertains to make and use the same.

This invention relates to closure devices for bottles, jugs, jars, and similar vessels; and the object thereof is to provide an improved device of this class particularly designed for use in closing a milk bottle, but which may be used for closing other vessels of this class, and with this and other objects in view the invention consists in a device of the class specified constructed as 20 hereinafter described and claimed.

The invention is fully disclosed in the following specification of which the accompanying drawing forms a part, in which the separate parts of my invention are designated by suitable reference characters in 25 each of the views, and in which:—

Figure 1 is a central vertical section of the neck of a milk bottle provided with my improved closure device, and showing the 30 same open to permit of the discharge of the contents of the bottle, the section of the closure device being on the line 1—1 of Fig. 2:—Fig. 2 is a plan view of the closure device detached and showing the 35 parts in the same position as in Fig. 1:—Fig. 3 a view similar to Fig. 2 but showing the parts of the closure device in position to close the bottle, and:—Fig. 4 a section on the line 4—4 of Fig. 2.

In the drawing forming part of this specification I have shown at *a* the neck of a milk bottle and said neck is provided in the top thereof with the usual annular groove *a*² forming, in the construction 40 shown, a bottom annular shoulder *a*³ and a downwardly and inwardly inclined top wall *a*⁴, but my invention is not limited to the exact form of the groove *a*².

In the practice of my invention I provide 50 a closure device *b* consisting of two similar disks *b*² of flexible and preferably elastic material, and which may be composed of celluloid, stiff paper, or similar fibrous material, and if paper or similar material is 55 employed it may be treated with paraffin or other substance so as to render it water

proof. The disks *b* and *b*² are pivotally connected at the center thereof, as shown at *c*, and each of said disks is provided in one side thereof with a large opening *d* which 60 is approximately semi-circular in form except at one end which is cut off at an angle to form a straight wall *e* and a thumb and finger piece *e*².

In the use of this closure device it is 65 forced into the neck of the bottle after the bottle has been filled and rests in the groove *a*², as shown in Fig. 1, and in order to open the bottle the top disk *b*² is turned, into the position shown in Figs. 1 and 2, and in 70 which position of said parts the contents of the bottle, or a part thereof may be discharged, as will be readily understood, and by turning the top disk back into the position shown in Fig. 3 the bottle will be 75 closed.

It will be seen that the disks *b* and *b*² are of exactly the same form and construction and the closure device may be inserted into the neck of the bottle in any position, 80 and instead of said closure device being inserted into the neck of the bottle after said bottle has been filled the bottle may be filled after the closure device has been inserted, as the desired contents may be poured into the 85 bottle through the opening *d* if desired. The disks *b*² are also provided each with an air vent opening *f* and these air vent openings are so arranged as to register when the said disks are in position to permit of 90 the discharge of the contents of the bottle.

Having fully described my invention what I claim as new and desire to secure by Letters Patent is:—

1. A closure device for bottles comprising 95 two similar flexible disks of the same transverse dimensions, said disks being pivoted together centrally thereof and adapted to rotate on their pivotal connections, and said disks being also provided with similar 100 large openings which are adapted to register when one of said disks is turned on the other, said disks being adapted to be inserted into the neck of a bottle with either side up, and means for turning each disk 105 on the other, said disks being also provided with vent openings adapted to register when the large openings register.

2. The combination with the neck of a bottle, provided in the top thereof with an 110 annular groove, of a closure device consisting of two similar flexible disks of the same

transverse dimensions, said disks being pivoted together centrally thereof and adapted to rotate on their pivotal connection, and said disks being also provided with similar 5 large openings which are adapted to register when one of said disks is turned on the other, and with means whereby either may be turned on the other.

In testimony that I claim the foregoing as my invention I have signed my name in presence of the subscribing witnesses this 23rd day of April, 1912.

GEORGE W. SCHELLER.
